United States Patent Office

Des. 177,772
Patented May 22, 1956

177,772

TANK TRAILER

Clifford Brooks Stevens, Milwaukee, Wis., assignor to The Heil Co., Milwaukee, Wis., a corporation of Wisconsin

Application November 14, 1955, Serial No. 38,880

Term of patent 14 years

(Cl. D14—3)

Fig. 1.

Fig. 2.

Fig. 3.

Fig. 1 is a view principally in side elevation of the tank trailer embodying my new design;

Fig. 2 is a perspective view looking principally at the side and rear; and

Fig. 3 is a perspective view looking principally at the side and front.

The characteristic features of my design are shown by full lines.

I claim:

The ornamental design for a tank trailer, substantially as shown and described.
